United States Patent Office.

J. A. PRICE, OF SCRANTON, PENNSYLVANIA.

Design No. 3,079, dated June 30, 1868.

DESIGN FOR A COOK'S RANGE.

The Schedule referred to in these Letters Patent and making part of the same.

TO ALL WHOM IT MAY CONCERN:

Be it known that I, J. A. PRICE, of Scranton, in the county of Luzerne, and State of Pennsylvania, have invented a new and useful Design for Cooking-Ranges; and I do hereby declare that the following is a full, clear, and exact description thereof, which will enable others skilled in the art to make and use the same, reference being had to the accompanying drawing, forming part of this specification, in which—

The drawing represents a perspective view of my design.

Similar letters of reference indicate like parts.

The general features of this design consist of the ornamental configuration shown and set forth, in combination with the general form of the range, all of which will now be described.

The box or body of the range is of an oblong form, having rounded corners *a a a*, and a projecting entablature, also with correspondent rounded corners *b b b*, which entablature forms the top of the range, and is provided with circular removable plates, as shown.

Projecting doors, with fluted edges or mouldings, are shown at *d d d d*, each door having a central wreath-device as shown at *e e e*.

The base, *A A*, projects from the plane of the sides of the range, and is ornamented with the oblong panelings, shown at *fff*.

This base has rounded corners corresponding with those of the entablature.

Having thus described my invention, I claim as new, and desire to secure by Letters Patent—

The design for a cooking-range, substantially as shown and described.

The above specification of my invention signed by me, this 4th day of March, 1868.

J. A. PRICE.
